United States Patent Office.

HENRY NEWBY, OF CINCINNATI, OHIO.

Design No. 4,901, dated May 9, 1871.

DESIGN FOR A THILL-CO尤LING.

The Schedule referred to in these Letters Patent and making part of the same.

I, HENRY NEWBY, of Cincinnati, Hamilton county, Ohio, have invented and produced a new and original "Design for an Elastic Thill-Coupling," of which the following is a specification.

Description of the Accompanying Drawings.

The accompanying drawings are a perspective view of a thill-coupling embodying my design.

General Description.

The lower part of the elastic coupling A has a rearwardly-curved portion, B, to which are secured the customary clips with which the device is attached to the front axle of the vehicle.

The upper part of the coupling terminates in two

forks or branches, C C', between which the thills are secured.

The branch C may be long enough to project under the cross-bar which unites the rear part of the thills.

Claim.

The design for a thill-coupling, as herein represented, the same being formed with elliptic curves A B and a bifurcated end, C C'.

In testimony of which invention I hereunto set my hand.

HENRY NEWBY.
